[57] **CLAIM**

The ornamental design for a vehicle steering wheel keyboard housing, as shown and described.

DESCRIPTION

FIG. 1 is a perspective view of a vehicle steering wheel keyboard housing showing my new design;

FIG. 2 is an enlarged front elevational view thereof;

FIG. 3 is an enlarged bottom plan view thereof; and

FIG. 4 is an enlarged side elevational view thereof. The broken lines in the drawings are for illustrative purposes only.
